DISPLAY STAND FOR BATTERIES
OR THE LIKE

Joseph Clement, Atlanta, Ga., assignor to Modern Metal Products Company, Greensboro, N.C., a corporation of North Carolina

Filed Oct. 21, 1966, Ser. No. 4,370

Term of patent 14 years

(Cl. D80—9)

FIG. 1

FIG. 3

FIG. 1 is a front perspective view of a display stand for batteries or the like embodying my new design;

FIG. 2 is a front elevational view thereof; and

FIG. 3 is an elevational view taken from one end thereof.

The broken line representation of batteries in FIGS. 1 and 2 are for purposes of illustration only.

I claim:

The ornamental design for a display stand for batteries or the like, as shown and described.
